DESIGN FOR A CONTAINER CLOSURE

Joel Kronman, New York, N. Y.

Application March 10, 1934, Serial No. 50,997

Term of patent 3½ years

To all whom it may concern:

Be it known that I, JOEL KRONMAN, a citizen of the United States, residing in the Borough of Queens, in the county of Queens, city and State of New York, have invented a new, original and ornamental Design for a Container Closure, of which the following is a specification, reference being had to the accompanying drawing forming part thereof.

Fig. 1 is a top plan view of a container closure, showing my new design.

Fig. 2 is a front view of the same.

I claim:

The ornamental design for a container closure, as shown.

JOEL KRONMAN.
